UNITED STATES PATENT OFFICE.

CARL A. KELLOGG, OF BATTLE CREEK, MICHIGAN.

PRINTING-MACHINE.

1,232,329.

Specification of Letters Patent. Patented July 3, 1917.

Application filed March 9, 1911. Serial No. 613,404.

To all whom it may concern:

Be it known that I, CARL A. KELLOGG, a citizen of the United States, and a resident of Battle Creek, Calhoun county, Michigan, 5 have invented certain Improvements in Printing-Machines, of which the following is a specification.

This invention relates to certain improvements in printing machines, and more particularly in that class or type of such machines which are especially designed and adapted for employment for printing webs from flat forms, and the object of the invention is to provide a machine of this general character, of a comparatively simple and compact nature, having certain features of novelty and improvement whereby the printing or perfecting of the web may be performed in a rapid and convenient manner and without excessive liability of breakage or tearing of the same such as often occurs during the operation of printing machines such as have heretofore in use.

The invention consists, in part, in a printing machine having means operable to constantly feed or drive a web to be printed past a flat form and coöperating impression cylinder wherein means is provided for imparting reverse reciprocatory movements to said flat form and cylinder, and for operating upon the web with said flat form and cylinder during those strokes of the form which correspond in direction with the travel of the web during impression, for the production of recurrent impressions of said form upon the web.

The invention consists further in a machine of the character above defined wherein means is provided for equalizing the movement of the form during impressions in such a manner as to permit substantially constant feeding movement of the web and dispense with the employment of equalizing devices such as have been customarily provided heretofore for varying the travel of the web to conform to variations in the movement of the printing form.

The invention also consists in a printing machine having a printing couple one of the elements of which is adapted for reciprocatory movement wherein means is provided for driving said reciprocatory element of the printing couple, including a plurality of driven members capable of alternate operation to impart reverse reciprocatory

movement to such element of the printing couple.

The invention consists further in a printing machine of this character wherein both the elements of the printing couple reciprocate in unison but in reverse directions, and wherein the form is driven at a substantially constant and uniform speed so as to conform to the travel of a web similarly driven, and wherein the reverse reciprocatory movement of the cylinder is utilized for shortening the strokes of the elements of the couple and otherwise facilitating the operation of the machine.

The invention also contemplates certain novel features of the construction, and combinations and arrangements of the several parts of the improved printing machine whereby certain important advantages are attained and the machine is rendered simpler, less expensive and otherwise better and more convenient and effective during use, all as will be hereinafter fully set forth.

The novel features of the invention will be carefully defined in the claims.

In order that my improvements may be the better understood, I will now proceed to describe the same with reference to the accompanying drawings in which I have illustrated one embodiment of my invention and wherein—

Figure 1 is a side elevation of the printing machine constructed according to my invention;

Fig. 2 is a fragmentary sectional view taken vertically and longitudinally through one end portion of the improved printing machine and showing the elements of one of the printing couples in one extreme position;

Fig. 3 is a view similar to Fig. 2 but illustrating the elements of the printing couple moved to their reverse extreme positions;

Fig. 4 is a fragmentary plan view showing certain features of construction of the form support and of the guiding means therefor;

Fig. 5 is a fragmentary sectional view taken horizontally through one end portion of the improved printing machine in the plane indicated by the line $a-a$ in Fig. 2;

Fig. 6 is a fragmentary section taken transversely and vertically through the upper part of the improved printing machine in the plane indicated by the line $b-b$ in Fig. 3;

Fig. 7 is a fragmentary detail view showing the cam for controlling the bed and cylinder actuating means; and

Fig. 8 is a detail view showing the adjustable gear connection for throwing the printing devices in and out of operation.

As shown in these views, the improved printing machine is provided with a frame 1 having two sets of reciprocatory web printing and perfecting devices, which are located, respectively, at lower and upper decks 2 and 3, the deck 2 being, in the structure herein shown, so positioned that its printing and perfecting devices travel in paths which 10 extend beyond the paths of the corresponding devices at the deck 3, so as to facilitate access to the respective printing and perfecting devices and at such an elevation above said deck 2 as is calculated to afford 20 space below it for the arrangement of certain parts of the driving mechanism, so that the length of the machine may be minimized without such excessive increase in the height of the upper deck as might render it difficult 25 to apply forms thereto.

The side portions of the frames 1 are spaced apart from each other at any necessary or desirable distance, dependent upon the width of the webs to be printed, and between said side portions are provided at the 30 respective decks 2 and 3 with oppositely arranged parallel and aligned guide members 4, 4 which serve as separate parts of the web printing and perfecting devices as will be hereinafter explained, and between the spaced guide portions 4, 4 at each deck 2 and 3 are arranged auxiliary guide members 5, 5, parallel with the guide members 4, 4 and spaced apart therefrom and from each 35 other and so constructed and arranged as to afford effective support for the reciprocatory form supporting members 6, 6 of the printing and perfecting devices at the respective decks 2 and 3.

As herein shown each of the members 6 is of such a length as to afford, adjacent to its opposite ends, separate form beds 7 and 8 adapted for receiving the flat forms 9 which are to be impressed upon the webs during 50 the printing and perfecting operations, and to provide, between the adjacent ends or edges of said form beds 7 and 8 an unobstructed space or opening 10, adapted in the construction herein shown, for the passages 55 in a vertical direction of the web to be printed, as clearly indicated at α^2 in Figs. 2 and 3, the dimensions of said space or opening 10, measured lengthwise of the member 6, being sufficiently in excess of the travel of 60 the member during its reciprocatory movement hereinafter explained, to effectively prevent interference with the free travel of said vertically extended part of the web.

Each member 6 is also provided, as clearly 65 shown in Figs. 2, 3 and 4 with oppositely ar-

ranged lateral tie portions 11, 11 which are extended along opposite sides of the central space or opening 10 in such a manner as to rigidly connect the beds 7 and 8 at opposite ends of said member, and 12, 12 represent 70 parallel bearers which are extended upon the opposite sides of the member 6 continually along the parts 7, 8 and 11, 11 so as to afford tracks along which correspondingly positioned bearing surfaces 14, 14 upon the 75 corresponding impression and perfecting cylinders 15 and 16 are adapted to travel during the movement of the beds and cylinders upon impression in a well known way. 17 and 18 represent racks at opposite sides 80 of each member 6 which are outside the bearers 12 one of these racks being adapted for engagement with gears 26 upon the respective cylinders 15 and 16 and the other of said racks being adapted for driving engagement with the form rollers 20, 20 adjacent to the respective cylinders 15 and 16 and adapted for movement in unison therewith to ink the forms 9 upon the respective beds 7 and 8 prior to each impression upon 90 the web.

Adjacent to the path of the vertical portion α^2 of the web which passes upward through guides at opening 10 in the member 6, the auxiliary guide members 5, 5 between the side portions of the machine frame are cut away so as to afford space for the upward travel of the web as indicated at 21 in Figs. 2 and 3 and at opposite sides of the space 21 so provided are extended transverse tie bars 22, 22 which are extended between the side portions of the machine frame and serve for the effective support of the auxiliary guides 5, 5. These auxiliary guides 5, 5 are provided in their upper surfaces with longitudinally extended grooves or channels 23 adapted for the reception of projections 24 upon the under surfaces of the beds 7 and 8 at opposite ends of the member 6, anti-friction rollers 25 being interposed between said projections and the bottoms of the grooves or channels in the auxiliary guides so as to facilitate the reciprocatory movement of the member 6 which is held securely in relation to the auxiliary 110 guides and prevented from rising above the same by a suitable means as clearly shown at 26 in Fig. 6.

The cylinders 15 and 16 at each deck of the machine are supported in a reciprocatory carriage which includes the side members 27, 27 adapted for endwise sliding movement upon the guides 4, 4 at opposite sides of the deck during the reciprocatory movement of the cylinders, these side members 125 being provided with upwardly directed bearings 28, 28 wherein the shafts 29 of the respective cylinders 15 and 16 are mounted to turn and said members are provided with arms 30 directed outward beyond opposite 130

sides of the respective cylinders 15 and 16 and tied or connected together by means of shafts 31 which are extended transversely across the machine and serve as supports for guide rollers 32 and 33 appropriately positioned at each side of each cylinder 15 and 16 to guide and direct the web to and from the impression surfaces thereof. The respective side members 27 of each cylinder carriage are provided with parts 34 and 35 engaged above and below the respective guides 4, 4 at opposite sides of the deck whereat such carriage is arranged, anti-friction rollers 36 being interposed between each 15 part 34 and 35 and the corresponding guide 4 so as to facilitate the reciprocatory movements of the cylinder carriage during the operation of the improved printing machine.

In the construction herein shown, the 20 form rollers 20, 20 for the forms at opposite ends of each member 6 are mounted upon the cylinder carriage at opposite sides of the cylinders 15 and 16 in operative relation to distributing rollers 37 which, during 25 the reverse reciprocatory movements of the carriage, are alternately presented to fountains 38, 38 supported upon the frame at opposite ends of the path of the cylinder carriage so that as said carriage is moved 30 in one direction, the distributing rollers at one end thereof receive ink from the corresponding fountain 38 while when the carriage is reversely moved, the inking devices at its opposite end receive ink from the corresponding fountain 38 at that end of the 35 path of said carriage.

It will be understood, of course, that although I have herein shown my invention embodied in a printing machine capable of 40 operation to print and perfect two webs at the decks 2 and 3, and although such construction and arrangement affords certain important advantages and improved results, and is included within my present invention, the said invention, considered in its 45 broad spirit is not limited to such duplication of the printing and perfecting devices.

In the structure shown in the drawings, the two webs α and α^1 are led into the machine from web rolls which may be located 50 in any convenient situations as, for example, at the end of the machine, and are passed between feed rolls 39 of any preferred or ordinary construction, so arranged and driven 55 as to cause a substantially uniform and continuous feeding movement of the web through the machine. There are provided for each of said webs α and α^1 , and appropriate to the corresponding deck 2 or 3, 60 lower and upper guide rolls 40 and 41, below and above the path of the corresponding form supporting member 6, and so arranged that the web from each feeding means 39 is received by the corresponding 65 lower guide roll 40 and is thence directed

vertically upward through the space 21 between the frame tie bars 22, 22, and through the space or opening 10 in the form supporting member 6, as indicated at α^2 , to the uppermost guide roll 41. Thence the web is 70 directed horizontally above the path of said member 6 to the guide roller 32 supported by the arms 30 of the corresponding cylinder carriage at the adjacent side of the printing cylinder 15, whence said web is 75 directed downward beneath said cylinder and around the impression surface thereof so as to adapt it for receiving the printing impression of the corresponding form.

From the printing cylinder 15, each web 80 is directed upward over and around the delivery guide roll 33 supported by the arms 30 at its side opposite to the guide roll 32, whence such web is directed horizontally over the frame to a guide roll 42 adjustably 85 mounted in bearings in the frame and capable of adjustment in the direction of travel of the web by means of screws 43, so as to permit the take-up necessary for securing registry of the impressions on opposite 90 sides of the webs with each other. From each take-up roll 42 the corresponding web α or α^1 is directed horizontally of the frame above the printing cylinder 15 to and around the receiving guide roll 32 supported in the 95 arms 30 of the corresponding cylinder carriage at the perfecting cylinder 16 at the end of such carriage opposite to the printing cylinder 15, whence said web is directed downward beneath said perfecting cylinder 100 and around the impression surface thereof in position to receive the perfecting impression of the corresponding form, after which such web is led upward over the delivery 105 guide roll 33 in the arms 30 at the opposite side of such perfecting cylinder 16, whence it passes to the delivery means 44 customarily provided at the former of the cutting mechanism.

By this arrangement of the web guides, it 110 will be seen that a loop is produced in each web between the guide roll 41 and the delivery means 44, and that the printing cylinder 15 operates upon the lower run α^3 of web comprised in such loop to print one side of 115 the web upon one of the forms of the corresponding form carrying member 6, while the web being turned or reversed at the take-up roll 42, the upper run α^4 comprised in such loop is passed beneath the perfecting cylinder 16, which is thereupon caused to operate 120 to print the opposite surface of the web and perfect the same upon the form at the opposite end of the form carrying member 6. In the structure shown, an auxiliary guide roll 125 45 is interposed between the lower deck 2 and the delivery means 44, to direct the web α^1 upward so that it may be run into the same cutting mechanism which receives the web α , but this is immaterial to my invention. 130

tion, since it will be obvious that the two webs may be carried to different cutting mechanisms when desired.

In the structure shown in the drawings, 5 the cylinders 15 and 16 at each deck 2 and 3 are rigidly connected together by the carriage whereon they are supported, so that they may be caused to move in unison during the reciprocatory movement of such carriage, and the form beds or supports at each deck are similarly tied or connected rigidly by the lateral parts of the carrying member 6, so that the two forms at each deck are likewise caused to move in unison with each 10 other during the reciprocatory movement of said member 6, and for the simultaneous reciprocation of the respective cylinder carriages and their corresponding form carrying members 6, 6, I provide actuating means 15 which I will now describe.

Said actuating means as herein shown is arranged for the conjoint actuation of the printing and perfecting devices at each of the respective decks 2 and 3 of the machine 20 and includes means operable at each deck to impart reciprocatory movement simultaneously to the form carrying member and cylinder carriage at such deck in reverse directions, the parts being so constructed and arranged that the forms are caused to be moved, during impression, in the direction of travel of the continuously moving web and at such velocity, compared with the reverse directional movement of the impression cylinders, as will insure the positioning 30 of successive impressions of the forms upon the web, the same occurring at alternate or similarly directed strokes of said forms, in such close succession and sequence as is necessary to avoid the presence of blank spaces 35 between them.

The actuating devices herein shown, include a driving shaft 46 journaled at the lower part of the machine frame beneath 45 the upper deck 3 and provided with a pulley 47 adapted to receive a belt or band whereby said shaft may be driven from a suitable source of power. The movement of said driving shaft 46 is communicated by means 50 of tooth gearing in trains 48 and 49 extended along the side of the frame, to shafts 50, 50 extended transversely across the machine frame beneath each of the respective decks 2 and 3. Where desired each of the gear 55 trains 48 and 49 may include a sliding gear 49^a adjustable lengthwise upon its supporting stud as indicated in Fig. 8, and adapted to be thrown in and out of mesh with its companion gears so as to permit of interrupting the operation of the actuating means at the corresponding deck of the machine.

Each such shaft 50 carries a pinion 51 having an elongated skew gear surface and held between the arms of a slide member or

carriage 52 supported for reciprocatory movement in a direction parallel with the length of the shaft 50 and adapted when moved to compel corresponding movement of such pinion 51 endwise upon the shaft 50, 70 without, however, interfering with the rotatory movement of said pinion in unison with said shaft 50, the latter being provided with an elongated key or feather 53 which permits endwise adjusting movement of the 75 pinion, while compelling the same to turn in unison with said shaft. The slide member or carriage 52 is provided with an anti-friction roll 52^a engaged with a grooved cam 54 mounted on a shaft 55 extended at right angles to the corresponding shaft 50 and driven by means of bevel gearing 56 from a stud 57 journaled in the machine frame and driven by means of gearing 58 from the gear train 48 or 49 whereby the corresponding 80 shaft 50 is driven from the driving shaft 46. 85

Each pinion 51 is arranged with its skew gear surface intermeshing with a correspondingly pitched skew surfaced gear wheel 60 mounted upon a shaft 61 extended 90 transversely across the machine frame beneath the corresponding deck 2 or 3 whereby it will be seen that movement is imparted to each such shaft 61 from the corresponding shaft 50 driven from the driving shaft 95 5 as above described under control of the cam 54 which is operable to vary the rotation of such shaft 61 at different points in each revolution thereof and the movement of said shaft 61 at each deck of the machine is communicated by gearing 62 to similar parallel shafts 63 and 64 extended horizontally across the machine frame beneath the corresponding deck 2 or 3, and so located that their central portions are extended transversely beneath one end of the form carrying member 6 at such deck, while their extremities are caused to project beyond the opposite sides of the machine frame beneath the oppositely arranged or spaced side 100 portions 27, 27, of the corresponding cylinder carriage which side portions, as clearly shown in Fig. 6 of the drawings, are mounted for reciprocatory movement upon the oppositely located parallel guides 4, 4 integrally produced upon the side portions of 105 said frame.

The arrangement of the auxiliary or intermediate guides 5, 5 at each deck 2 and 3 of the machine is such that a space or opening 67 is present between them at the central part of the form carrying member 6, said space or opening being extended parallel with the direction of travel of said member during its reciprocatory movement, and said space or opening 67 is of such dimensions as to receive a pendent rack surface 66 secured upon the under surface of one of the terminal bed supporting portions 7 of said member 6, beneath which the cen- 110 115 120 125 130

tral portions of the corresponding shafts 63 and 64 are also extended.

Gearing 62 whereby said shafts 63 and 64 are driven from the variably moving shaft 5 61 is located out of line with the center of the machine as indicated in Figs. 5 and 6 so as to avoid interference with the rack 66 and upon the respective shafts 63 and 64 midway of the width of the frame are secured bed actuating members 68 and 69 respectively, which have mutilated gear surfaces 70, 70 adapted during the turning movement of said shafts to be alternately engaged with the toothed surface of the 10 pendent rack 66 of the corresponding form carrying member 6.

The structure and arrangement of the gearing 62 is such that the respective transverse shafts 63 and 64 are simultaneously 20 driven in opposite directions as indicated by the arrows at *a*, *a'*, in Figs. 2 and 3, and the arrangement of the mutilated gear surfaces 70 of the bed actuating members 68 and 69 on said respective shafts is such that, 25 during the turning movement of said shafts, the mutilated gear surface 70 of one actuating member, as 69 for example, is first engaged with the toothed surface of the rack 66, while the mutilated gear surface 70 of 30 the other actuating member 68, is disengaged therefrom, whereby the form carrying member whereon said rack is secured is moved in one direction. Afterward, during further rotatory movement of the shafts 35 63 and 64, the mutilated gear surface 70 of the other actuating member, as 68 for example, is brought into mesh with said rack 66 while the mutilated gear surface 70 of the actuating member 69 is disengaged 40 therefrom whereby the bed carrying member is driven in the reverse direction.

The construction and arrangement of the parts is such as to insure disengagement of the mutilated gear surface 70 of each actuating member from the rack 66 of the form carrying member simultaneously with the engagement of the mutilated gear surface of the other actuating member with said rack, and the mutilated gear surfaces of the 45 members 68 and 69 moving in opposite directions during their alternately occurring times of engagement with the rack of the form carrying member serve to impart rapid reciprocatory movement thereto.

To permit of lessening the strains which would otherwise be imposed upon the gear surfaces of the members 68 and 69 and rack 66 during the reversal of movement of the form carrying member at the opposite ends 55 of its stroke, I have shown the mutilated gear surfaces 70 of the respective actuating members 68 and 69 each somewhat less than 180° in extent and at opposite ends of the rack 66, I have provided pendent studs 71, 60 which when the member 6 is recipro-

cated, alternately come into engagement with pins or rollers 72 suitably positioned at the sides of the respective actuating members 68 and 69, the engagement of each stud 71 with its corresponding pin or roller 72 occurring at the termination of the form carrying member and at or prior to the time of engagement of the mutilated gear surface 70 of the member whereon such pin or roller is mounted with the rack 66 whereby the strains imposed upon the newly engaged mutilated gear surface 70 at the instant of reversal of movement of the form carrying member are minimized to lessen the liability of breakage. 75

The structure and arrangement of the bed actuating devices is clearly illustrated in Figs. 2 and 3 of the drawings wherein the parts are shown in sectional side elevation as they appear at opposite ends of the travel 80 of the member 6, and for the operation of the cylinder carriages at the respective decks 2 and 3 of the machine, I have provided similar actuating means as clearly indicated in Figs. 1 and 6 of the drawings, the oppositely arranged side portions of the cylinder carriage having pendent racks 66^a which are adapted, during the reverse reciprocatory movements of the cylinder carriages to be alternately engaged with the mutilated gear 85 surfaces of cylinder actuating members 68^a and 69^a secured upon the oppositely projecting extremities of the shafts 63 and 64 beyond the opposite sides of the machine frame. 90

The structure and arrangement of the parts of the cylinder actuating means thus provided, and their operation, are exactly similar to the structure, arrangement and operation of the bed actuating means above 95 described and shown in Figs. 2 and 3 of the drawings excepting that, since the cylinder carriages are desired, to travel through a longer path than that of the member 6 and to be moved reversely to the travel of the 100 form carrying member 6, the cylinder actuating members 68^a and 69^a are made larger in diameter than the corresponding bed actuating members, and are secured upon the respective shafts 63 and 64 in positions reverse to the positions of the bed actuating members 68 and 69. In this way it will be seen that when the bed actuating member 68 comes into operation as shown in Fig. 3 to drive the member 6 in one direction by the 105 engagement of its mutilated gear surface 70 with the rack thereof, the mutilated gear surfaces 70 of the cylinder actuating members 69^a at opposite ends of the shaft 64 are brought into engagement with the racks 66^a 110 at opposite sides of the cylinder carriage in such a manner as to drive the latter in a direction reverse to the travel of the form carrying member 6. It will also be seen that when the bed actuating member 69, as 115

shown in Fig. 2, is brought into operation to reversely drive the member 6 by the intermeshing of its mutilated gear surface 70 with the rack 66 of such member, the mutilated gear surfaces 70 of the cylinder actuating members 68^a at opposite ends of the shaft 63 are brought into engagement with the rack 66^a at opposite sides of the cylinder carriage to drive the same in a direction reverse to the travel of the member 6. The structure and arrangement of the cylinder actuating devices hereinabove set forth, whereby the cylinders are caused to traverse paths longer than the paths traversed by the form supporting members 6, are of material importance in a machine such as that to which I have herein shown my present improvements applied for use, since when the beds are driven with a substantially uniform velocity during the period of impression, the requisite slowing of the same at the ends of their reciprocations, essential for the accomplishment of the reversal of their movement, results in a certain shortening of the actual time of impression, to compensate for which the excessive travel of the cylinders suffices. This function of the traveling cylinders, moving reversely to the travel of the members 6 is altogether independent of the shortening of the stroke arising from such movement of the cylinders as is complementary to the travel of said members 6 during the period of impression.

Furthermore it will be apparent that the employment of the traveling cylinders moving in directions reverse to the travel of the members 6 is of very material advantage in a machine such as that to which I have herein shown my invention applied, since such reverse travel of the members of the printing couples serves not alone to shorten the stroke, with resultant reduction in the size and weight of the machine, and in the expenditure of power needful for its operation, but also greatly lessens the time during which it is necessary to maintain substantially absolute synchronism between the movements of the forms and traveling web, whereby the liability of breakage of the web and interruption of the operation of the machine is also much lessened.

At each deck of the machine herein shown the shafts 29, 29 of the respective cylinders 15 and 16 are provided at their opposite ends with eccentric bushings 73 mounted for turning movement in the upwardly extended bearing portions 28 of the cylinder carriage and capable of adjusting movement so as to be operable to raise and lower the cylinders relatively to the form supporting member 6 traveling beneath them as is requisite for tripping or throwing such cylinders on and off impression. The eccentric bushings 73, 73 are provided with arms 74, 74 extended downward at the

opposite sides of the cylinder carriages and at each deck of the machine, these pendent arms 74, 74 of the eccentrics 73, 73 at opposite ends of the printing and perfecting cylinders 15 and 16 are tied or connected together by means of rods or links 75, 75 extended lengthwise along the opposite sides of the carriage above its side members 27, 27, so as to operate to compel movement of the eccentric bushings appropriate to said cylinders 15, 16 in substantial unison with each other.

The rods or links 75, 75 at each deck of the machine are provided with spaced collars 76, 76 positioned midway between the cylinders 15 and 16 and at the opposite sides of the cylinder carriage, and between the collars thus provided at the opposite sides of the carriage are arranged arms or abutments 77, 77 upwardly extended from the machine frame. These arms or abutments are adapted, when the carriage is moved in one direction, to contact upon the collars 76, 76 nearest one end of said carriage as the latter approaches the end of its stroke, so as to operate to shift the rods or links endwise in one direction and correspondingly rock the eccentric bushings 73, 73 for the respective cylinders in unison with each other. When the carriage nears the end of its travel in the opposite direction, the said arms or abutments 77, 77 at opposite sides thereof will operate by contact upon the collar 76, 76 nearest the opposite end of the cylinder carriage, to again shift said rods or links 75, 75 endwise, but in the direction opposite to that in which they were before shifted, in order that the eccentric bushings 73, 73 of the printing and perfecting cylinders may be again rocked and caused to properly trip the printing and perfecting cylinders.

The eccentric bushings of the cylinders 15 and 16 at each deck of the machine may be similar in throw, but in the embodiment of my invention herein set forth, said bushings at one cylinder, as 15, of each deck of the machine are set reversely to the bushings at the other cylinder 16 of the same deck, so that when in the operation of the machine, the bushings are rocked upon the approach of the cylinder carriage to one end of its stroke, one of the cylinders, as 15, at said carriage will be tripped or thrown off impression, while the other cylinder, as 16, at the same carriage will be tripped or thrown upon impression, and when the carriage nears the limit of its travel in the reverse direction, upon the next or succeeding stroke, its cylinders will be again tripped or thrown into opposite relative positions, the cylinder 15, for example, being then tripped or thrown upon impression, while the cylinder 16 is tripped or thrown off impression.

The improved printing machine being thus adapted for operation at each deck 2

and 3, to print upon the web with one form of the member 6 during the travel of said member in one direction, and to print upon said web with the form 9 at the opposite end 5 of said member 6 during the reverse travel of such member occurring at its next succeeding stroke, it will be seen that the load is more evenly and constantly opposed to the driving devices, so that straining of the 10 parts is prevented and a more economical utilization of the power is permitted, and since the upper and lower runs x^8 and x^4 in which the web is formed above each deck of the machine travel in opposite directions, 15 as indicated by the arrows in Figs. 2 and 3, it is permitted to print upon each such run of the web with that form which is at any particular stroke of the form carrying member 6, conforming in direction of movement 20 with the travel of that run of the web.

The employment of the actuating devices hereinbefore described, including the mutilated gear members 68 and 69 alternately engageable with the rack 66 of the form 25 carrying member 6 to drive the same at a substantially constant and uniform velocity, permits of moving the form during impression in accurate conformity with the constant and uniform travel of the continuously 30 moving web, the pinion 51 being held stationary and prevented from endwise movement along the shaft by the engagement of the roller 52^a within the concentric portion of the slot of cam 54 throughout the time of 35 impression, so as to effectually avoid or prevent variations in the velocity with which the said member 6 is impelled while the cylinder is on impression.

The travel of the form carrying member 40 6 as herein shown and for purposes which will be hereinafter pointed out, is somewhat in excess of what may be considered to be actually essential for the impression of the forms 9, 9 carried upon said member 45 upon the web, intervals of time being thus provided prior to and after each impression, during which the said member 6 is permitted to be reversed, and the formation of the cam groove in cam 54 as shown in 50 the detail elevation, Fig. 7, is such as to cause repeated movements of the pinion 51 in the same direction lengthwise along the shaft 50, one of these endwise movements of the pinion occurring prior to the time 55 of impression and just prior to the reversal of the direction of travel of said member before or at the commencement of its impression stroke, and being so directed relatively to the inclination of the skewed gear 60 surfaces of the pinion 51 and gear 60 as to operate to slow down or decrease the speed of travel of said member 6 during reversal. After completion of this endwise movement 65 of pinion 51, the latter will be returned by cam 54 to its initial position and in the

further rotation of said cam 54 and subsequently to the time of impression and prior to or during the reversal of the direction of travel of said member 6 at the termination of its impression stroke the end- 70 wise movement will be repeated, being directed similarly to the first-mentioned endwise movement of the pinion, so as to operate likewise for slowing down and decreasing the velocity of travel of said member 6, 75 the endwise slowing movements thus imparted through said cam 54 and pinion 51 serving to lessen the strains which would otherwise be imposed upon the parts at the opposite ends of the travel of said member 6. 80

It will also be evident that since the mutilated gear members 68^a and 69^a which operate to drive the cylinder carriage at each deck 2 and 3 of the improved machine 85 are secured upon the same shafts 63 and 64 whereon the corresponding actuating members 68 and 69 for the form carrying member 6 are mounted, the movement imparted by said members 68^a, 69^a will also 90 be controlled by the cam 54 and sliding pinion 51 at the corresponding deck of the machine in exact conformity to the control exerted upon said member 6 as above described, so that as the form carrying member 95 6 is slowed down to permit its reversal upon its approach to the termination of its stroke in one direction, the corresponding cylinder carriage, approaching the termination of its stroke in the opposite direction 100 will be similarly slowed down in order that the strains imposed upon the mechanism may be lessened during reversal of the cylinder carriages.

In the operation of the improved printing 105 machine constructed according to my invention, the form carrying member 6 and cylinder carriage at each deck are reciprocated in reverse directions and the web to be printed and perfected thereby is fed continuously 110 into the machine by the feeding devices 39 and is passed upwardly through the central opening 10 of the member 6 and directed by the guide rollers 41, 32, 33 and 42 through the printing and perfecting devices to the delivery roll at the cutting mechanism 44 or equivalent device to which the web is to be supplied, the construction and arrangement of the parts being such that the web is caused to travel at a 115 substantially constant and uniform speed through the printing and perfecting devices at all times, both during and after impression, whereby it is permitted to dispense with the employment of equalizing or compensating devices for varying the speed of movement of the web or for stopping and starting the same, such as have been customarily provided heretofore in flat bed 120 web printing machines. 125

The formation of the member 6 with the central opening 10 between its spaced bed portions 8, 8, and the extension of the web upwardly therethrough as indicated at x^2 , 5 between the forms 9, 9, at opposite ends of said member 6, permits the web to be conveniently led into and through the improved machine in such a manner as to facilitate the turning thereof in order that when one 10 surface of said web shall have been printed upon by the cylinder 15 and its coöperating form 9, the opposite surface of such web may be turned lowermost and presented in position to receive the impression of the 15 form at cylinder 16, and this peculiar arrangement and structure of the parts also avoids the employment of turning bars or equivalent devices and permits a straight run of the web through the machine from 20 the web roll to the cutting mechanism or equivalent delivery 44.

The simultaneous reciprocation of the form and cylinders in opposite directions, 25 permits not only of shortening the travel of such parts so that the machine may be made much more light and compact in construction, but also facilitates the printing, at each impression stroke of the form, an extent of web greater in length than the 30 travel of the form during impression. It will thus be seen that if it be desired, in the construction of the printing machine embodying my improvements, to make the form and cylinder to travel equal distances 35 in opposite directions during impression, the continuously moving web, being driven at a substantially uniform and constant speed throughout the operation of the improved printing machine, both on and off 40 impression, will travel during impression to an extent equal substantially to one-half the length of the form, or of the impression thereby produced upon the web, and after such impression, said web will travel a further 45 distance also equal substantially to one-half the length of the form, or of the impression produced thereby upon the constantly moving web so that, at the commencement of the next succeeding impression 50 stroke of the form, the web will have been sufficiently far advanced to permit the next succeeding impression of the form to be produced thereon closely adjacent to the termination of the last preceding impression. 55

In the embodiment of my invention herein shown, however, I have provided such a construction and arrangement of the form and cylinder actuating means, and of the tripping mechanism for throwing the printing couples on and off impression, that the impression cylinders are caused to travel, during the impression stroke, a sufficient distance over and above one-half of the

length of the form, and of the impression 65 thereby produced upon the web, to insure the travel of the form roller 20 appropriate to said cylinder and form over the entire extent of the form, in order that the same may be properly and completely inked by 70 such form roller during the movement of the cylinder carriage whereon said roller is supported, prior to the commencement of the impression. Since the actuating means for the form and cylinder of each printing 75 couple are constructed and arranged to operate in synchronism, it will be understood that the total extent of travel of the form during each stroke of the member 6 is somewhat greater than is absolutely requisite for 80 the completion of an individual impression upon the web during the printing coöperation of the form and cylinder.

For practical purposes also, since the structure and arrangement of the form actuating means hereinbefore described is such that the form is caused to travel at a substantially uniform and constant speed during the impression, conforming to the rate of travel of the constantly moving web, it 85 is also desirable that the total travel of the elements of each printing couple in the improved printing machine to which my invention is herein shown applied, shall be so increased above what is absolutely essential 90 for impression or printing coöperation of such elements as will permit sufficient slowing down of such elements just prior to the termination of their several strokes or reciprocations as may be necessary or desirable 95 for effecting the needful reversal of movement at the end of each such stroke without the imposition of excessive or dangerous strains upon the operative parts of the machine. In the improved printing machine 100 herein shown, the excess travel of the elements of each printing couple occurring immediately subsequent to the completion of each impression and made necessary by the peculiar arrangement of the inking mechanism as above explained, is utilized as a part 105 of the excess travel requisite for slowing down the elements of the printing couple prior to the reversal of their direction of travel at the terminations of their impression strokes. One of the operations of the cam 54, to slide the pinion 51 endwise along the shaft 50 is timed to occur during such excess travel of the elements of the couple just subsequent to the completion of the impression, so that the extent of travel of such elements is correspondingly decreased beyond what would otherwise be necessary for the most practical results. 115

It will be evident, of course, that the relative travel of the elements of the printing couples in the machine constructed according to my invention and shown herein, is not 120 125

arbitrarily fixed in any particular ratio, but is susceptible of such variation as may be thought desirable or convenient in view of the nature of the work to be performed.

- 5 While it is desirable in some cases, as in the machine herein shown, to decrease the travel of the form during impression below the length of the printing surface thereof, or of its impression upon the web, in order that 10 one impression may be produced upon the web immediately succeeding a prior impression, or only separated therefrom sufficiently to afford margins for the printed pages, this is in no wise essential to the broad 15 spirit and principles of the present invention since it will be obvious that it may in certain cases be desirable to produce spaced impressions upon the web, in which event it is only needful to increase the travel of the 20 form during impression so as to partially or wholly neutralize the compensatory function of the reversely traveling impression cylinder.

It will also be understood that where, as 25 in the embodiment of my invention herein shown, the form and web travel forwardly during impression, it would appear to be impossible to move the form upon its impression stroke through a greater distance 30 than one-half the length of web fed through the machine for each impression of such form, but since the form is idle and not upon impression during its retracting or return stroke, it will be seen that by appropriate formation of the cam groove in the cam 54 at its point which engages the roller 52^a during such return stroke, the return movement of the form may be speeded up by proper endwise movement of the pinion 35 51 so as to compensate for a certain excess in travel of the form during its impression stroke beyond one-half the length of web fed through the machine for each impression.

40 45 Furthermore it will be understood that it is not absolutely essential to the broad spirit of the invention, that the web should be fed through the machine at a constant or uniform speed, although this is desirable 50 for practical reasons. Where desired, the web may be variably or otherwise fed or pulled through the machine without departure from the invention. In the machine herein shown, this may be accomplished by properly modifying the web feeding means and the conformation of the 55 groove in cam 54.

From the above description of my improvements, it will be seen that the printing 60 machine constructed according to my invention is of an extremely simple and comparatively inexpensive nature, and is particularly well adapted for use by reason of the convenience and increased speed with which

it may be operated, and of the ease and 65 facility with which the necessary adjustments may be made, and it will also be obvious from the above description that the device is susceptible of some modification without material departure from the principles and spirit of the invention, and for 70 this reason I do not desire to be understood as limiting myself to the precise formation and arrangement of the several parts herein set forth in carrying out my invention in 75 practice.

Having thus described my invention, what I claim and desire to secure by Letters Patent is—

1. A printing machine having a printing 80 couple including two members one of which is a bed adapted to support a flat form and the other of which is a cylinder coöperating with the bed, web feeding means operable to feed a web between the bed and cylinder, 85 means operable to throw one member of the printing couple on or off impression, and means for imparting reciprocatory movement to the bed and cylinder in reverse directions and through different distances, 90 said means being operable to compel movement of the bed at a constant rate of travel while on impression.

2. A printing machine having a bed 95 adapted to support a flat form, a cylinder coöperating with the bed, means for imparting reciprocatory movements to said bed and cylinder in reverse directions simultaneously during impressions, and web feeding means operable to feed a web between 100 the bed and cylinder during impressions at a constant and uniform rate of travel.

3. A printing machine having a bed adapted to support a flat form, a cylinder coöperating with the bed, means for imparting reciprocatory movements to said bed and cylinder in reverse directions and simultaneously during impressions, and operable to compel substantially constant and uniform travel of the bed during impression, and 110 web feeding means operable to feed a web between the bed and cylinder at a velocity conforming to the substantially constant and uniform travel of said bed during impressions. 115

4. A printing machine having a bed adapted to support a flat form, a cylinder coöperating with the bed, means for imparting reciprocatory movements to said bed and cylinder in reverse directions and simultaneously during impressions, the reciprocatory movements of the bed being less in extent than those of the cylinder, and web feeding means operable to feed a web between the bed and cylinder during impressions at a substantially constant and uniform rate of travel. 125

5. A printing machine having a bed

adapted to support a flat form, a cylinder coöperating with the bed, means for imparting reciprocatory movements to the bed and cylinder in reverse directions and simultaneously during impressions, and operable to compel substantially constant and uniform travel of the bed during impressions and web feeding means operable to feed a web continuously and at a constant 10 and uniform speed between the bed and cylinders both during and between impressions.

6. A printing machine having a bed adapted to support a flat form, a cylinder coöperating with the bed, means for imparting reciprocatory movements to the bed and cylinder in reverse directions and simultaneously during impressions, and operable to compel substantially constant and 15 uniform travel of the bed during impressions, the reciprocatory movements of the bed being less in extent than those of the cylinder, and web feeding means operable both during and between impressions, to 20 feed a web between the bed and cylinder at a speed conforming to the velocity with which the bed travels during impressions.

7. A printing machine having a bed adapted to support a flat form, a cylinder coöperating with the bed, web feeding means 30 operable to feed a web between the bed and cylinder at a substantially constant and uniform rate of travel, and means operable during impressions for imparting reversely 35 directed reciprocatory movements to the bed and cylinder, the bed and cylinder, when thus reversely moved during impressions, traveling a distance so much less than the length of the individual impressions 40 produced by the form upon the web as is requisite to compensate for the travel of the web between impressions.

8. A printing machine having a bed adapted to support a flat form, a cylinder coöperating with the bed, means for imparting reciprocatory movements to said bed and cylinder in reverse directions and simultaneously during impressions, said means being operable to compel substantially 45 constant and uniform travel of the bed during impression, and to reduce the velocity of the bed at the termination of each of its strokes, and web feeding means operable to feed a web between the bed and cylinder at a velocity which conforms during impressions to the travel of said bed during impressions.

9. A printing machine having a bed adapted to support a flat form, a cylinder coöperating with the bed, means for imparting reciprocatory movements to said bed and cylinder in reverse directions and simultaneously during impressions, said means being operable to compel substan-

tially constant and uniform travel of the bed during impression, and to reduce the velocity of the bed at the termination of each of its strokes, and web feeding means operable both during and between impressions, to feed a web between the bed and cylinder at a speed conforming to the velocity with which the bed travels during impressions.

10. A printing machine having a bed adapted to support a flat form, a cylinder coöperating with the bed, means for imparting reciprocatory movements to said bed and cylinder in reverse directions and simultaneously during impressions, said means being operable to compel substantially constant and uniform travel of the bed during impression, and to compel, variable travel of said bed between impressions, and web feeding means operable to feed a web between the bed and cylinder at a velocity which conforms during impressions with the travel of the bed during impressions.

11. A web printing machine having a bed adapted to support a flat form, a cylinder coöperating with the bed, means for imparting reciprocatory movements to said bed and cylinder simultaneously and in reverse directions during impressions, said means being operable to compel substantially constant and uniform travel of the bed during impressions and to reduce the velocity of the bed at the termination of each of its strokes, and said means being further operable to move the cylinder in excess of the travel of the bed to compensate for the reduction of the velocity of the bed at the termination of each stroke as aforesaid, and web feeding means operable to feed a web between the bed and cylinder at a velocity which conforms to the travel of the bed during impressions.

12. A printing machine having a bed adapted to support a flat form, a cylinder coöperating with the bed, a form roller operable to ink a form carried by the bed and traveling in unison with the cylinder, means for imparting reciprocatory movements to said bed and cylinder in reverse directions and simultaneously during impressions, the reciprocatory travel of one of said parts when moved by such means being greater than the reverse reciprocatory travel of the other part, and such excess travel being adapted to compel travel of the form roller over the full length of the form upon the bed, and web feeding means operable to feed a web between the bed and cylinder during impressions at a substantially constant and uniform rate of travel.

13. A printing machine having a printing couple operable to print recurrently upon a web and including members capable of relative travel during impression in re-

verse directions and through different distances, one of said members being an impression cylinder, a form roller spaced from but traveling with the cylinder of the printing couple and operable to ink the printing form thereof, and means operable to feed a web to be printed to said printing couple at a substantially uniform and constant rate of travel during impressions, the total relative travel of the members of the printing couple during each stroke being not less than the length of web fed by the feeding means for such impression plus the distance between centers of the form roller and the cylinder of the printing couple.

14. A printing machine having a printing couple including a reciprocatory member, and means for driving said reciprocatory member of the printing couple including a plurality of variably driven devices capable of alternate operation to impart reversely directed movements to said member, and each operable to impart varying movements to the latter.

15. A printing machine having a printing couple including a reciprocatory member, means for driving said reciprocatory member of the printing couple including a plurality of devices operable alternately to impart reversely directed variable movements to said member, and capable of operation to compel constant travel of said member during impression and variably driven means for imparting movement to said alternately operable devices.

16. A printing machine having a printing couple including a reciprocatory member, means for actuating said reciprocatory member of the printing couple including a plurality of devices operable alternately to impart reversely directed variable movements to said member, said actuating means being capable of operation to compel constant travel of said reciprocatory member of the printing couple during its impression strokes while on impression, and to vary the rate of travel thereof adjacent to the ends of such impression strokes and variably driven means for operating said actuating means.

17. A printing machine having a printing couple including a reciprocatory member, means for actuating said reciprocatory member of the printing couple including reversely driven devices alternately engageable with said member to impart reverse variable movements thereto, said means being also operable to vary the rate of travel of said reciprocatory member adjacent to the ends of its strokes and variably driven means for operating said actuating means.

18. A printing machine having a printing couple including a reciprocatory member, means for driving said reciprocatory mem-

ber of the printing couple including reversely rotatable driven devices alternately engageable with said member to impart reverse reciprocatory variable movements thereto, and mechanism operable to vary the speed of rotation of said reversely driven devices.

19. A printing machine having a printing couple including reversely reciprocatory members, web feeding means operable to feed a web between said members, and means operable to drive said members of the printing couple reversely and simultaneously including a plurality of driven devices capable of alternate operation to impart reversely directed reciprocatory movement to each of said members.

20. A printing machine having a printing couple including reversely reciprocatory members, web feeding means operable to feed a web between said members, and means operable to impart reciprocatory movement to said members of the printing couple simultaneously in reverse directions, and capable of operation to compel constant and uniform travel of one of the members during impression.

21. A printing machine having a printing couple including reversely reciprocatory members, web feeding means operable to feed a web between said members, means operable to impart reciprocatory movement to said members of the printing couple simultaneously in reverse directions and means in controlling relation to said driving means and operable to compel constant and uniform travel of one of said members of the printing couple during impression.

22. A printing machine having a printing couple including reversely reciprocatory members, means operable to impart reciprocatory movement to said members of the printing couple simultaneously in reverse directions and means in controlling relation to said driving means and operable to compel constant and uniform travel of one of said members of the printing couple during impression and to vary the travel of such member between impressions.

23. A printing machine having a printing couple including reversely reciprocatory members, means operable to impart reciprocatory movement to said members of the printing couple simultaneously in reverse directions and including a plurality of driven devices capable of alternate operation to impart reversely directed movement to each of said members of the printing couple, and means in controlling relation to said driving means and operable to compel constant and uniform travel of one of said members of the printing couple during impression, and to vary the travel of such member between impressions.

24. A printing machine having a printing couple including reversely reciprocatory members, and means for driving said respective members of the printing couple including reversely rotatable driven devices alternately engageable with each of the members of the printing couple to impart simultaneous reverse reciprocatory movement thereto.
- 10 25. A printing machine having a printing couple including reversely reciprocatory members, web feeding means operable to feed a web between said members, and means operable to impart reciprocatory movement 15 to said members of the printing couple simultaneously and in reverse directions including a plurality of driven devices capable of alternate operation to impart reversely directed movement to each of said 20 members and operable to drive the same at different speeds.
26. A printing machine having a printing couple including a form carrying member the opposite end portions whereof afford 25 form supports, and the central portion of which is apertured between said form supports, guiding means extended beneath the form carrying member and operable to support the same and along which said member 30 moves, said guiding means being also apertured midway of its length, and means for feeding a web wherewith said couple is in printing relation through said apertures of the form carrying member and of said guiding 35 means.
27. A printing machine having a form carrying member, the opposite end portions whereof afford form supports and the central portion of which is apertured between 40 such form supports, a cylinder carriage having first impression and perfecting cylinders adapted to coöperate with forms carried upon the respective form supports of the form carrying member to perfect a web, 45 means for feeding a web through said aperture of the form carrying member and between the forms thereof, said first impression and perfecting cylinders and a common impression controlling device coöperating 50 with each of said cylinders and operable to throw said cylinders simultaneously, the one on and the other off impression.
28. A printing machine having a printing 55 couple including a reciprocatory member having cam surfaces, means operable to feed a web between the members of said couple with a constant speed, means for driving said reciprocatory member of the printing 60 couple including reversely rotatable driven devices alternately engageable with said member to impart reciprocatory movement thereto first in one direction and then in the reverse direction and operable to move 65 said member with a constant speed while on impression, and means carried by said reversely driven devices engageable with the cam surfaces of said member of the printing couple adjacent to opposite ends of its stroke to terminate the reciprocatory movement thereof.
29. A printing machine having a printing couple including a reciprocatory member having cam surfaces, means operable to feed a web between the members of said couple 70 with a constant speed, means for driving said reciprocatory member of the printing couple including reversely driven mutilated gears alternately engageable with said member to impart reverse reciprocatory movement thereto and operable to move said member with a constant speed while on impression, and projections carried by the gears engageable with the cam surfaces of said member of the printing couple at opposite ends of its stroke to limit the reciprocatory movement thereof.
30. A printing machine having a printing couple including reversely reciprocatory members, and means operable to drive said 75 members of the printing couple simultaneously in reverse directions including reversely driven mutilated gears alternately engageable with each of the members of the printing couple to impart simultaneous reverse reciprocatory movement thereto.
31. A printing machine having a printing couple including reversely reciprocatory members and means for driving said respective members of the printing couple including reversely rotatable driven devices alternately engageable with each of the members of the printing couple to impart simultaneous reverse reciprocatory movement thereto and operable to drive one of said 80 members of the printing couple at a substantially constant and uniform rate of travel during impression.
32. A printing machine having a printing couple including reversely reciprocatory members and means for driving said respective members of the printing couple including reversely rotatable driven devices alternately engageable with each of the members of the printing couple to impart simultaneous reverse reciprocatory movement thereto, and operable to drive one member of the printing couple at a substantially constant and uniform rate of travel during impression and at a variable speed between 85 impressions.
33. A web printing machine having a printing couple including two members, one of which is a bed adapted to support a flat form and the other of which is an impression cylinder coöperating with the form supported upon the bed, actuating means to impart reciprocatory movement to the bed 90

operable to move the same with a uniform velocity during the period of impression and to permit reduction of the velocity of said bed at the ends of its strokes, and web feeding means operable to feed a web lengthwise between the bed and cylinder during impression with a uniform velocity conforming to that of the reciprocatory bed during the period of impression, and means operable 5 to compensate for the travel of the web during reduction of the velocity of the bed.

34. A web printing machine having a printing couple including two members one of which is a bed adapted to support a flat form and the other of which is an impression cylinder co-operating with the form supported upon the bed, web feeding means 15 operable constantly to feed a web lengthwise between the bed and cylinder with a uniform velocity, actuating means to impart reciprocatory movement to the bed operable to move such bed, during the period of impression, with a uniform velocity conforming to that with which the web is constantly 20 fed between such bed and the impression cylinder by the web feeding means and also operable to permit reduction of the velocity of the bed at the ends of its strokes, and means co-operating with the cylinder to move 25 the same complementally to the bed to an extent sufficient to compensate for the travel of the web during reduction of the velocity of the bed.

35. A web printing machine having a printing couple including two members one of which is a bed adapted to support a flat form and the other of which is an impression cylinder co-operating with the form supported upon the bed, web feeding means to 30 feed a web between the bed and cylinder with a uniform velocity during the period of impression, actuating means for imparting reciprocatory movement to the bed adapted to move the same, during the period 40 of impression, with a uniform velocity conforming to that with which the web is fed between the bed and cylinder during the period of impression and operable to vary the velocity with which the bed is driven 45 between impressions, and means operable to compensate for the travel of the web during variation of the velocity with which the bed is driven.

36. A web printing machine having a printing couple including two members one of which is a bed adapted to support a flat form and the other of which is an impression cylinder co-operating with the form supported upon the bed, means for feeding a web between the bed and cylinder during the period of impression, means for moving the bed, during such period of impression, to an extent less than the length of the form supported upon the bed, operable to drive 55

said bed prior to and after the period of impression with a velocity less than that with which such bed is driven during such period of impression, and means for moving the cylinder, during the period of impression, complementally and in a direction reverse to the travel of the bed, and to an extent sufficient to compensate for the reduction in velocity of the bed prior to and after the period of impression. 65

37. A web printing machine having a printing couple including two members one of which is a bed adapted to support a flat form and the other of which is an impression cylinder co-acting with the form upon the bed, means for feeding a web between 70 the bed and cylinder with a uniform velocity during the period of impression, means for moving the bed, during such period of impression, to an extent less than the length of the form supported thereupon, operable to 75 drive such bed, during the period of impression, with a uniform velocity conforming to that with which the web is fed between the bed and cylinder during such period, and also operable to reduce the velocity of the bed prior to and after the period of impression, and means for moving the cylinder, during the period of impression, complementally and in a direction reverse to the travel of the bed and to an extent sufficient to compensate for the reduction in velocity of the bed prior to and after the period of impression. 80

38. A web printing machine having a printing couple including two members one of which is a bed adapted to support a flat form and the other of which is an impression cylinder co-acting with the form supported upon the bed, means for moving the bed, during the period of impression, with a uniform velocity, means for feeding a web between the bed and cylinder operable to move the web in synchronism with the bed during such period of impression, and means for moving the cylinder, during such period of impression, complementally and in a direction reverse to the travel of the bed, operable to shorten the time during which synchronism is requisite between the bed and traveling web. 100

39. A web printing machine having a printing couple including two members one of which is a bed adapted to support a flat form and the other of which is an impression cylinder adapted to co-act with a form supported upon the bed, means for moving the bed, during the period of impression, with a uniform velocity and to an extent less than the length of the form supported thereupon, and operable to move the bed, prior to and after the period of impression, with a velocity less than that with which such bed is driven during such period, means 105

for feeding a web between the bed and cylinder, operable to move such web in synchronism with the bed during such period of impression, and means for moving the cylinder, during such period of impression, complementally and in a direction reverse to the travel of the bed, and to an extent sufficient to compensate for the reduction in velocity of the bed prior to and after the period of impression, and operable to shorten the time during which synchronism is requisite between the bed and traveling web.

40. A web printing machine having a printing couple including a bed and cylinder, actuating means to impart reciprocatory movement to the bed operable to permit reduction of the velocity of said bed after the period of impression and prior to reversal of the direction of travel thereof, 15 means for feeding a web lengthwise between the bed and cylinder, operable to feed such web at a velocity substantially like that at which the bed is moved while on impression and with a velocity different from that of the bed during the reduction of velocity of the bed after impression and prior to reversal of the direction of travel thereof, and means coöperating with the cylinder to move the same complementally to the bed to an 25 extent sufficient to compensate for the travel of the web during reduction of the velocity of the bed while off impression.

41. A web printing machine having a printing couple including a bed and cylinder, actuating means to impart reciprocatory movement to the bed operable to permit reduction of the velocity of said bed while off impression, means for feeding a web lengthwise between the bed and cylinder, operable to feed such web at a velocity substantially like that at which the bed is moved while on impression, and with a velocity different from that of the bed when the velocity of the latter is reduced while off impression, and means for moving the cylinder complementally to the bed and to an extent sufficiently in excess of the travel of said bed to compensate for the difference between the velocities of the web and bed, 45 due to the reduction of the velocity of said bed while off impression.

42. A web printing machine having a printing couple including a bed and cylinder, actuating means to impart reciprocatory movement to the bed operable to permit reduction of the velocity of said bed while off impression, means for feeding a web lengthwise between the bed and cylinder, operable to feed such web at a velocity substantially like that at which the bed is moved while on impression, and with a velocity different from that of the bed when the velocity of the latter is reduced while off impression, means for moving the cyl-

inder complementally to the bed to an extent sufficiently in excess of the travel of the bed to compensate for the difference between the velocities of the web and bed, due to the reduction of the velocity of said bed while off impression, and inking means traveling with the cylinder and adapted to traverse the form upon the bed during the movement of said cylinder while off impression.

43. A web printing machine having a printing couple including a bed adapted to support a form and a cylinder adapted to coact with the form supported upon the bed, impression controlling means, means for reciprocating the bed operable to move the same, during the time of impression, to an extent less than the length of the form supported upon the bed, and also operable to move said bed with reduced velocity while the same is off impression, means for feeding a web lengthwise between the bed and cylinder, operable to move said web with a velocity substantially like that at which the bed is moved while on impression, but at a velocity different from that at which the bed is moved while off impression, and means for moving the cylinder, during the time of impression, complementally and in a direction reverse to the travel of the bed, and to an extent sufficient to compensate for the time consumed during reversal of the direction of movement of the bed and also to compensate for differences between the travel of the web and bed due to reduction in the velocity of the bed while off impression.

44. A web printing machine having a printing couple including a reciprocatory bed and an impression cylinder adapted to coact with a form upon the bed and having a reciprocatory carriage, means for feeding a web between the bed and said cylinder, and driving means including reversely driven gears engaged directly with the bed and cylinder carriage to drive the same simultaneously in reverse directions.

45. A web printing machine having a printing couple including a reciprocatory bed and an impression cylinder adapted to coact with a form upon the bed and also capable of reciprocatory movement, means for feeding a web between the bed and said cylinder, and driving means including reversely driven devices adapted for intermittent driving engagement with the bed and cylinder, respectively, to compel simultaneous reverse reciprocatory movements thereof.

46. A web printing machine having a printing couple including two members one of which is a reciprocatory bed and the other of which is an impression cylinder adapted to coact with a form upon the bed, and also capable of reciprocatory movement,

means for feeding a web between the bed and said cylinder, and driving means including devices in driving relation with the respective members of the printing couple alternately, and adapted for intermittent driving engagement with said respective members to compel movement of said members simultaneously but in reverse directions.

Copies of this patent may be obtained for five cents each, by addressing the "Commissioner of Patents, Washington, D. C."

In witness whereof I have hereunto signed my name in the presence of two subscribing 10 witnesses.
